UNITED STATES PATENT OFFICE.

JOHN B. GRIFFIN, OF NEWINGTON, CONNECTICUT.

DESIGN FOR A NOVELTY PICTURE-BRACELET.

55,788.

Specification for Design.

Patented July 13, 1920.

Application filed October 17, 1919. Serial No. 331,487. Term of patent 7 years.

To all whom it may concern:

Be it known that I, JOHN B. GRIFFIN, a citizen of the United States, residing at Newington, county of Hartford, State of Connecticut, have invented a new, original, and ornamental Design for a Novelty Picture-Bracelet, of which the following is a specification, reference being had to the accompanying drawings, forming part thereof.

Figure 1 is a perspective of the novelty picture bracelet, opposite ends of which are fastened together so as to form a loop showing my new design.

Fig. 2 is a side elevation of the same.

In the drawings, *a* is a flexible band which encircles the wrist and is provided with

means for being clasped together. This band is of the shape and form as shown, consisting of narrowed web portions *b*, intervening, enlarged background portions *c*. The portions *c* follow the outline and shape of the picture frame mounted on such background so as to provide a semi-individual background for each picture frame. The picture frames are indicated at *d* and are circular in shape provided with a transparent inset and frame upraised, and are mounted one to each background of the band.

I claim:

The ornamental design for a novelty picture bracelet, as shown in the drawings.

JOHN B. GRIFFIN.
